UNITED STATES PATENT OFFICE.

JOSEPH DORIN, OF ROUEN, FRANCE.

APPARATUS FOR HOISTING PIECES OF FURNITURE AND SIMILAR OBJECTS THROUGH WINDOWS OF UPPER STORIES OF BUILDINGS.

1,045,131.

Specification of Letters Patent.

Patented Nov. 26, 1912.

Application filed April 23, 1912. Serial No. 692,678.

To all whom it may concern:

Be it known that I, JOSEPH DORIN, a citizen of the French Republic, residing at Rouen, of the Republic of France, have invented certain new and useful improvements in an apparatus for hoisting pieces of furniture and similar objects through the windows of upper stories of buildings, of which the following is a specification.

10 This invention relates to an apparatus for lifting pieces of furniture and similar objects through the windows of the upper stories of buildings.

15 In the accompanying drawings the invention is shown by way of example.

Figure 1 shows the apparatus in front elevation mounted in the window. Fig. 2 is a side view of the apparatus, the window being shown in vertical section. Fig. 3 is a 20 view similar to Fig. 1 showing another form of construction of the apparatus. Fig. 4 is a vertical section of Fig. 3.

The apparatus essentially consists of two vertical supports which are each composed 25 of two parts, a lower tubular part 4 and an upper rod 6. The tubular part 4 has a nut 5 at its upper end and the lower part 7 of the rod 6 is threaded so that it can be screwed into said nut 5. The upper end of 30 the rod 6 is fork-shaped. The lower ends 2 of the supports are placed upon the window sill so that they are slightly inclined toward the outside, the lower ends of said supports bearing against the lower cross 35 frame 2 of the window. In the upper fork-shaped end 8 of each of the supports 6 a rack 15 is placed which stands perpendicular to the lintel 3 of the window. The racks 15 have each at the front end and in the 40 lower edge a notch 12 which engages with the bottom of the fork-shaped end 8 of the corresponding support. Shackles 9 are fixed upon the racks 15 by means of clamping screws 10 which engage with the teeth 11 45 of the racks. The shackles have a horizontal threaded boring at the upper end into which horizontal screw spindles 13 are screwed which have clamps 14 adapted to bear against the front and rear of the lintels 3 in order to 50 securely fix the apparatus in the window. The racks have at their front ends upwardly projecting U-shaped extensions 17 in which the cross bar 16 is mounted at the middle of which a winch 18 is suspended.

It seems not to be necessary to further explain the function of the apparatus as it is absolutely clear from the foregoing description and from the accompanying drawings. 55

The apparatus can be adjusted according to the thickness of the wall owing to the 60 racks which are carried by the upper end of the supports.

According to the form of construction shown in Figs. 3 and 4 vertical stays 19 are mounted in the U-shaped extensions 17 of 65 the racks 15. These stays are either made of wood or of metal. In the upper ends 19^a of said vertical stays 19, notches are provided in which the cross bar 16 is mounted. These stays 19 further have lugs 20^a into which 70 screw spindles 20 are screwed which bear with their inner ends against the wall or the lintel of the window. These screw spindles 20 have nuts 21 the position of which upon the spindles is adjusted according to 75 the distance between the stays 19 and the wall. Eyes 22 are fixed in the rear surface of the cross bar 16 and chains 23, 24 are attached to these eyes. The chain 23 is placed around the screw spindle 14 of the left hand 80 side of the rack while the chain 24 is guided around the spindle 14 of the right hand side of the rack so that said chains cross each other and securely maintain the cross bar 16 in its position. The free ends of the 85 chains are attached to one of the links of the chain. The winch 18 is mounted upon the middle cross bar 16. The apparatus is mounted in the same manner as the apparatus shown in Figs. 1 and 2. 90

I claim:

1. An apparatus for hoisting pieces of furniture and other similar objects through the windows of buildings, comprising in combination two adjustable supports mounted 95 upon the window sill, upper fork-shaped ends of said supports, horizontal racks mounted in said fork-shaped ends, shackles in front of and behind the wall mounted upon the said rack, set screws on the lower 100 end of said shackles fixing the shackle upon the rack, horizontal internally threaded sleeves at the upper ends of said shackles, screw spindles having clamps at their inner ends screwed into said horizontal sleeves, a 105 U-shaped upwardly projecting extension at the front end of each rack, a cross bar mounted in said U-shaped extensions and a

winch suspended to said cross bar substantially as described and shown and for the purpose set forth.

2. An apparatus for hoisting pieces of furniture and other similar objects through the windows of buildings, comprising in combination two adjustable supports mounted upon the window sill, upper fork-shaped ends of said supports, horizontal racks mounted in said fork-shaped ends, shackles in front of and behind the wall mounted upon the said rack, set screws on the lower end of said shackles fixing the shackle upon the rack, horizontal internally threaded sleeves at the upper ends of said shackles, screw spindles having clamps at their inner ends screwed into said horizontal sleeves, a U-shaped upwardly projecting extension at the front end of each rack, a vertical stay

mounted in said U-shaped extension having 20 a notch at the upper end, a cross bar mounted in said notches, a winch suspended to said cross bar, lateral lugs of said stays, horizontal screw spindles screwed into said lugs so that they bear against the wall, a nut 25 upon said screw spindle for regulating the distance of the stay from the wall, chains attached to said cross bar and guided each around the screw spindles of the rack at the other end of the scaffolding, substantially 30 as described and shown and for the purpose set forth.

In testimony whereof I affix my signature in presence of two witnesses.

JOSEPH DORIN.
